(57) **CLAIM**

The ornamental design for a tablet chair, as shown and described.

DESCRIPTION

FIG. 1 is an isometric view of a tablet chair incorporating our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a rear elevation view thereof; and,

FIG. 7 is an isometric view of the tablet chair with the tablet rotated to an alternate position.

The portions shown in phantom illustrate environment and form no part of the claimed design.
